DAVID J. DOLAN, OF CLEVELAND HEIGHTS, OHIO, ASSIGNOR TO THE CARDEL COMPANY, INC., OF CHESTER, PENNSYLVANIA, A CORPORATION OF DELAWARE

MOTOR GOVERNING DEVICE

Application filed November 14, 1931. Serial No. 574,992.

This invention relates to means for limiting the power output of an internal combustion engine as of an automotive vehicle, whereby the engine, particularly when new, 5 cannot be damaged by incompetent or unauthorized operation. The invention is generally an improvement over that shown in my Patent No. 1,854,735, issued April 19, 1932, wherein is shown an attachment for temporarily limiting the opening of the usual engine throttle valve, which attachment is adapted to be sealed in position, and removed after it has fulfilled its purpose.

The objects of the present invention are 15 to accomplish additional results and advantages. The invention contemplates the provision of an auxiliary throttle valve permanently incorporated in the fuel supply system for the engine, and adjustable as to 20 its throttling effect.

Another object is to provide novel and simplified means for sealing the auxiliary throttle in any of its adjusted positions, and for sealing also the carburetor connection 25 with the manifold in which the auxiliary throttle is located. Still another object is to associate with this throttle valve, a connection for the windshield wiper of the vehicle, or other pneumatic device to be actuated 30 from the vacuum in the manifold.

The exact nature of this invention together with further objects and advantages thereof will be apparent from the following description taken in connection with the accompanying drawing, in which Fig. 1 is a view in elevation of pertinent portions of 35 the fuel supply system of an internal combustion engine showing an embodiment of my invention associated therewith; Fig. 2 is a view of the same but showing a different adjustment of the parts; Fig. 3 is a detail section as in the plane of line 3-3, Fig. 1; and Fig. 4 is a sectional detail as in the plane of line 4-4, Fig. 3.

With reference now to the drawing, 1 is the inlet portion of a manifold flanged as at 2 for connection with the carburetor 3 which is similarly flanged as usual so that bolts 4 complete the connection. The carburetor 3 is provided with the usual throttle valve 5.

According to my invention I provide in the manifold 1 an auxiliary valve comprising a disk 6 which is the valve proper, mounted upon a stem 7 which bears in the manifold walls and extends beyond one of them so that the valve 6 may be set. As indicated in Figs. 3 and 4 the stem 7 has a squared or otherwise deformed portion 8, and the manifold is provided with a boss 9 there adjacent. In order that the stem 7 and thus the valve 6 may be controlled I provide a plate 10 having an opening fitting the deformity of the portion 8 of the stem. In this plate are a plurality of holes 11 spaced upon an arc concentric with the stem. 55 The manifold 1 is drilled and threaded to receive a screw 12 passing through one of the openings 11 in the plate 10, whereby, dependent upon the opening 11 selected, the valve may be secured in any of a plurality of adjusted positions.

The plate 10 is provided with another opening 13 located in the lip 14 projecting from the plate and preferably bent outwardly as indicated. The head of the screw 12 has a transverse opening 15, as do the bolts 4. Thus the wire 16 may be threaded as indicated Figs. 1-3, through both bolts 4, the opening 15 in the screw 12 and the opening 13 in the plate 10, and secured with the seal 17; and neither the screw 12 may be loosened to change the setting of the plate 10 and thus of the valve 6, nor can either of the bolts 4 be loosened to allow air to enter 75 the manifold at its connection with the carburetor.

In order that a convenient connection may be had with the passage in the manifold, so that use may be made of the vacuum therein for actuation of an auxiliary such as a windshield wiper, preferably the stem 7 of the auxiliary valve is provided with a bore 18 leading out to the end of the stem 7. Within the passage in the manifold the stem 7 is cut away as indicated Fig. 4 to receive the valve 6 which is riveted as at 19, so that the bore 18 communicates with the manifold passage. The projecting end of the stem 7 is threaded as at 20 to receive a nut 21 by which the tube 22 is secured with the stem 80 85 90 95 100

so that the hollow of the tube communicates with that of the passage in the manifold.

In operation, as when the vehicle of which the described apparatus is a part, is to be delivered overland to its first purchaser, the auxiliary valve 6 is set and sealed in nearly closed position. This setting is had by selecting the proper one of the openings 11 in the plate 10 for insertion of the screw 12; 10 and the sealing of the valve in this position is made by threading the wire 16 as shown Figs. 1 and 2 and sealing together the ends of the wire.

If the vehicle is received by the dealer or 15 owner with the seal unbroken this is conclusive evidence that the engine has not been overspeded in the delivery trip.

Thereafter, as when the owner entrusts the vehicle to an employee, he may set the auxiliary valve in a wider open position, by 20 selecting another of the openings 11 in the plate, and resealing the parts as before.

It will be noted that the auxiliary valve 6 may be adjusted and sealed in adjusted position without disturbing the pneumatic connection of the tube 22.

Regardless of the setting of the valve 6, the usual throttle valve 5 on the carburetor is manipulated as always to control the engine; but the maximum engine output is limited by the setting of the valve 6.

What I claim is:

1. In a fuel supply system for an internal combustion engine including an inlet manifold and a carburetor, bolt means adapted to secure said carburetor with said manifold, a valve in said manifold, means for securing said valve in a selected one of a plurality of adjusted positions, and means associated 20 with said securing means for sealing the valve in any of said positions, said sealing

means including an external member associated with said bolt means to prevent turning of the latter.

2. In a fuel supply system for an internal combustion engine including an inlet manifold and a carburetor, bolt means adapted to secure said carburetor with said manifold and having openings, a valve adapted to control the manifold passage and having a stem adapted to extend without said manifold, with a deformed portion, a plate fitting over said portion and thereby keyed with said stem, said plate having a plurality of openings, a screw extending through one of said plate openings and adapted to be turned into said manifold and having an opening, and a sealing member extending through the opening in said screw and one of said plate openings and the openings in said bolt means. 35

3. In an inlet manifold for an internal combustion engine, a valve, means for securing said valve in a plurality of adjusted positions, means for supporting a carburetor including bolt means, and means for sealing the valve in any of its said positions and including a member associated with said bolt means to prevent turning of the latter.

4. In an inlet manifold for an internal combustion engine, a valve arranged to control the manifold passage having a stem extending beyond said manifold, with a deformed portion, a plate fitting over said portion and thereby keyed with said stem, said plate having a plurality of openings, a screw extending through one of said openings and turned into said manifold and having an opening, and a sealing member extending through the opening in said screw and another of said openings in said plate. 395
